UNITED STATES PATENT OFFICE

157,179

DOOR

Ulyus G. Massey, Ensley, Ala.; Emma Jean Massey, executrix of said Ulyus G. Massey, deceased, assignor to Emma Jean Massey, Ensley, Ala.

Application November 26, 1948, Serial No. 149,818

Term of patent 7 years

(Cl. D13—2)

To all whom it may concern:

Be it known that I, Ulyus G. Massey, a citizen of the United States, residing at Ensley, in the county of Jefferson and State of Alabama, have invented a new, original, and ornamental Design for a Door, of which the following is a specification, reference being had to the accompanying drawing, forming part thereof.

Figure 1 is a front elevational view of a Door, showing my new design, and

Figure 2 is a cross-sectional view, taken substantially in the plane of the line 2—2 in Figure 1.

The rear elevational view, not shown, is substantially the same as the front elevation view illustrated.

The dominant features of my design reside in the portion shown in full lines.

I claim:

The ornamental design for a door, as shown and described.

ULYUS G. MASSEY.
